US0D1041651S

(12) **United States Design Patent** (10) Patent No.: **US D1,041,651 S**
(45) Date of Patent: ** Sep. 10, 2024

(54) **CATHETER CLIP**

(71) Applicant: **Route 92 Medical, Inc.**, San Mateo, CA (US)

(72) Inventors: **David Rhodes**, San Mateo, CA (US); **Tony M. Chou**, San Mateo, CA (US); **John Miller**, San Mateo, CA (US)

(73) Assignee: **Route 92 Medical, Inc.**, San Mateo, CA (US)

(**) Term: **15 Years**

(21) Appl. No.: **29/830,999**

(22) Filed: **Mar. 16, 2022**

(51) LOC (14) Cl. **24-02**

(52) U.S. Cl.

USPC **D24/128**

(57) **CLAIM**

The ornamental design for a catheter clip, as shown and described.

DESCRIPTION

FIG. 1 is a top, front, and left side perspective view of a catheter clip, showing our design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, front, and left side perspective view thereof, shown in an example environment of use.

The broken line showing of parts of the drawings is included for the purpose of illustrating use and environment and forms no part of the claimed design.

1 Claim, 5 Drawing Sheets
